TAKEDOWN FIREARM

David M. Williams, New Haven, Conn., assignor
to Western Cartridge Company, New Haven,
Conn., a corporation of Delaware

Application January 21, 1943, Serial No. 473,111

11 Claims. (Cl. 42—75)

The present invention relates to improvements in takedown firearms, that is to say, firearms of the type in which the barrel, together with the parts organized therewith, is readily separable from the stock, for purposes of cleaning, repair, compactness in transportation, etc.

One of the objects of the present invention is to provide a superior takedown firearm construction comprising a stock-unit and a barrel-unit which are demountably secured together with capacity for ready separation, all in a manner which is simple, reliable and effective.

Another object of the present invention provides a firearm-structure of the character referred to in which the stock-unit and the barrel-unit are coupled together by superior means which will automatically compensate for slight variations in the dimensions of the two units with reference to a nominal standard.

A further object is to provide a takedown firearm-structure in which superior means is provided for releasably holding the stock-unit and the barrel-unit together, and which means will function over long periods of use to maintain the two said units in tight and firm engagement despite appreciable wear of the contacting parts.

Still another object of the present invention is to provide superior means whereby a stock-unit and a barrel-unit of a firearm-structure may be releasably coupled together in such manner that vibration between the two said units is kept at a minimum when the firearm is assembled and in use.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view in side elevation of one form of takedown firearm embodying the present invention;

Fig. 2 is a broken view partly in side elevation and partly in vertical central-longitudinal section of the portion of the firearm-structure adjacent the rear portion of the barrel-unit;

Fig. 3 is a transverse sectional view taken on the line 3—3 of Fig. 2;

Fig. 4 is a view corresponding to Fig. 2 but showing the barrel-unit in a tilted position with respect to the stock-unit preparatory to the interlocking of the two said units;

Fig. 5 is a transverse sectional view of the barrel-unit and taken on the line 5—5 of Fig. 4;

Fig. 6 is a broken top or plan view of the central portion of the stock-unit;

Fig. 7 is a longitudinal sectional view taken on the line 7—7 of Fig. 6;

Fig. 8 is an underside view of the receiver together with a portion of the barrel;

Fig. 9 is a top or plan view of the trigger-plate;

Fig. 10 is a view thereof in side elevation;

Fig. 11 is a perspective view of the tensioning-fixture;

Fig. 12 is a perspective view of the head-plate; and

Fig. 13 is a perspective view of the tensioning-screw or member.

The particular takedown firearm herein chosen for purposes of illustrating the present invention includes a stock-unit generally designated by the reference character 15, and a barrel-unit generally designated by the reference character 16.

The stock-unit 15 includes a buttstock-portion 17 and an integral forestock-portion 18. At about the junction point of its buttstock-portion 17 and forestock-portion 18, the stock-unit 15 is formed with a vertical-longitudinal passage 19 extending therethrough from top to bottom and designed and adapted for the reception of portions of the firearm in a manner as will be hereinafter described. Leading forwardly from the vertical-longitudinal passage 19 just referred to, is a deep upwardly-opening longitudinal groove 20 located mainly in the upper portion of the forestock-portion 18.

Leading rearwardly from the upper rear-portion of the vertical passage 19 in the stock-unit 15 is a longitudinal groove 21 which is relatively-

shallow as compared to longitudinal groove 20 before referred to. Leading downwardly from the groove 21 just referred to is an upwardly-opening recess 22 communicating at its forward end with the rear end of the vertical passage 19, as is especially well shown in Figs. 2, 4 and 7. The lower portion of the rear wall of the vertical passage 19 is formed with a notch 23 which latter, in turn, has leading rearwardly from it a transverse anchoring-groove 24. Extending vertically between the shallow recess 22 and the notch 23 in the portion of the stock-unit 15 immediately to the rear of the passage 19 therein, is a vertical passage 25. To the rear of the

passage 25 just referred to, the stock-unit 15 is

formed with an upwardly-opening cylindrically-contoured socket 26.

Installed partly in the upwardly-opening recess 22 and partly in the vertical passage 25 of the stock-unit 15 is a tensioning-fixture 27 having at its upper end a plate-like head 28 from substantially the central portion of which depends an integral sleeve 29. The plate-like head 28 of the tensioning-fixture 27 is accommodated in the relatively-shallow upwardly-opening recess 22 in the stock-unit 15, while the sleeve 29 of the said fixture snugly fits into the vertical passage 25 in the said stock-unit. The upper face of the plate-like head 28 of the fixture 27 is preferably transversely curved to substantially conform to the transverse curvature of the longitudinal groove 21 in the stock-unit 15 to the rear of the large vertical passage 19 therein. The forward portion of the upper face of the head 28 of the fixture 27 preferably slopes rearwardly and upwardly to provide a cam-surface 30, as shown. To the rear of the sleeve 29, the plate-like head 28 of the fixture 27 is provided with a transverse clearance-groove 31 for purposes as will hereinafter appear.

The lower portion of the sleeve 29 of the fixture 27 is internally threaded and has screwed thereinto the relatively-large-diametered body-portion 32 of a relatively-long tensioning-screw or -member generally designated by the reference character 33. Formed integral with and upwardly extending from the body-portion 32 just referred to is a tension-pin 34 materially smaller than the axial bore in the sleeve 29 of the tensioning-fixture 27 and extending upwardly beyond the upper surface of the head 28 of the said tensioning-fixture.

Located in the notch 23 formed in the stock-unit 15 adjacent the lower rear-portion of the large vertical passage 19 therein, is a head-plate 35 having a rearwardly-projecting anchoring-tongue 36 fitting into the anchoring-groove 24 in the stock-unit 15. In its upper face, the head-plate 35 is formed with an upwardly-opening recess 37 receiving the lower end of the sleeve 29 of the tensioning-fixture 27, as is shown especially well in Figs. 2 and 4. On its lower forward portion, the head-plate 35 is formed with a rearwardly-and-downwardly-sloping cam-surface 38. The body-portion 32 of the tensioning-screw 33 before referred to extends upwardly through the head-plate 35 which is suitably recessed in its lower portion for the accommodation of the head of the said screw. As thus constructed and arranged, the screw 33 serves to couple the head-plate 35 to the sleeve 29 of the tensioning-fixture 27.

Returning now to the barrel-unit 16, the same for purposes of description may be considered as comprising a barrel 39, a receiver 40 and a trigger-plate 41. In a manner usual in firearms, the barrel 39 is rigidly coupled to and projects forwardly from the forward portion of the receiver 40, while the trigger-plate unit is located below the receiver 40 and is coupled thereto in any suitable manner such, for instance, as the manner presently to be described.

The receiver 40 is accommodated mainly in the upper portion of the large vertical passage 19 in the stock-unit 15, though its rear-portion is accommodated in the longitudinal groove 21 in the said buttstock-portion 17, and the forward end of the said receiver is accommodated partially in the longitudinal groove 20 in the fore-

stock-portion 18. The barrel 39 fits into the longitudinal groove 20 just referred to and for a portion of its length is covered by the barrel-cover 42 (Fig. 1) which, like the stock-unit 15, is preferably formed of wood or other suitable heat-insulating and shock-absorbing material.

As is shown especially well in Figs. 4, 5 and 8, the receiver 40 is formed in its under-portion, adjacent its forward end, with a vertical magazine-receiving passage 43 and adjacent its rear end with a vertical clearance-passage 44. The magazine-receiving passage 43 and the clearance-passage 44 just referred to, are partially divided from each other by an integral web 45 extending transversely of the receiver about midway the length thereof and integrally uniting the respective opposite side-walls thereof. The forward lower portion of the receiver 40 is formed with a central-longitudinal downwardly-opening groove 46 communicating at its rear with the magazine-receiving passage 43 and intersecting the extreme forward end of the receiver 40. Spaced slightly below the web 45 of the receiver 40, the said receiver is formed with two longitudinal inwardly-projecting coupling-ribs 47-47, one of which projects inwardly from each of the respective opposite side-walls of the said receiver, as is especially well shown in Fig. 5.

Resting respectively upon the coupling-ribs 47-47 of the receiver 40 is one of two corresponding longitudinal coupling-ribs 48-48 respectively laterally offsetting in opposite directions from the respective side-faces of a lug-like extension 49 upstanding from the trigger-plate 41 substantially midway the length thereof.

At its forward upper portion, the trigger-plate 41 is formed with an upwardly-projecting stabilizing-lug 50 which normally fits within the longitudinal groove 46 in the lower forward portion of the receiver 40. Intermediate its coupling-ribs 48-48 and its stabilizing-lug 50, the trigger-plate 41 is also formed with a magazine-receiving passage 51 registering with and leading downwardly from the magazine-receiving passage 43 in the receiver 40.

As thus coupled to the receiver 40, the trigger-plate 41 is "hung" so to speak, about midway of its length by the engagement of its coupling-ribs 48-48 with the upper surfaces of the respective coupling-ribs 47-47 of the receiver 40. Thus, any downward strain imposed upon the rear end of the trigger-plate 41 will tend to cause the said trigger-plate to rock longitudinally about its coupling-ribs 48-48 as a center, and thereby urge the forward end of the trigger-plate upwardly. Such movement, however, is prevented by the engagement of the upper surface of the stabilizing-lug 50 of the trigger-plate with the top surface of the groove 46 in the forward end of the receiver 40. The distance from the coupling-ribs 47-47 to the lower rear end of the trigger-plate 41 will permit the rear end of the trigger-plate to yield downwardly relative to the receiver 40, for purposes as will hereinafter appear.

The lower rear portion of the receiver 40 which normally overlies the plate-like head 28 of the tensioning-fixture 27 in the stock-unit 15, is formed with a socket 52 receiving the upper end of the tension-pin 34. Normally, the rear wall of the socket 52 just referred to acts as a forwardly-facing coupling-abutment which is engaged with the rear face of the tension-pin 34, as is especially well shown in Fig. 2.

As an additional precaution against the for-

ward displacement of the fixture 27, the plate-like head 28 thereof is formed with a hole 53 receiving the upper end of a stud 54, the lower portion of which latter has a drive fit in the socket 52 in the stock-unit 15.

The barrel-unit 16 may include any suitable breach-bolt, firing-mechanism, trigger, etc., which parts, however, do not per se form essential features of the present invention, and therefore require no description herein.

For purposes of transmitting the shock of discharge from the barrel-unit 16 to the stock-unit 15, the said stock-unit is formed on each of the respective opposite sides of its relatively-large vertical passage 19 with one of two forwardly-facing recoil-abutments 55-55 extending vertically in the said passage 19. Each of the said abutments 55-55 is normally engaged by one of two vertical rearwardly-facing recoil-abutments 56-56, one of which is formed on each of the respective opposite sides of the trigger-plate 41 about midway the length thereof.

In separating the barrel-unit 16 from the stock-unit 15, the said barrel-unit is tilted upwardly into substantially the position in which it is shown by broken lines in Fig. 1 and by full lines in Fig. 4, after the barrel-cover 42 and associated bands or the like have been first removed. During the operation just referred to, the lower rear corner of the receiver 40 will fulcrum in the clearance-groove 31 in the upper face of the tensioning-fixture 27 as the lower rear corner of the trigger-plate 41 swings forwardly and slightly upwardly. When the barrel-unit has been swung sufficiently, the lower rear corner of the trigger-plate 41 will be fully clear of the head-plate 35 in the rear portion of the passage 19 in the stock-unit 15, whereupon the said barrel-unit may be moved directly upwardly to thereby disengage the socket 52 at the rear end of the receiver 40 from the upper end of the tensioning-pin 34.

When it is desired to reassemble the barrel-unit 16 with the stock-unit 15, the forward end of the barrel-unit is tilted upwardly with respect to the stock-unit and then lowered so that the trigger-plate and adjacent parts enter the upper end of the vertical passage 19 in the said unit 15 and until the socket 52 in the rear lower portion of the receiver 40 is slipped over the upper end of the tensioning-pin 34. Now by depressing the forward end of the barrel-unit 16, the rear end of the same will fulcrum in the clearance-groove 31 in the upper face of the tensioning-fixture 27 and when the rear lower portion of the trigger-plate 41 engages with the cam-surface 33 of the head-plate 35, a downward strain will be applied on the rear end of the said trigger-plate. As the downward swinging movement of the forward portion of the barrel-unit 16 is continued, the parts will ultimately reach the positions in which they are particularly well shown in Fig. 2 prior to reaching which position, the vertical recoil-abutments 56-56 on the trigger-plate 41 will have been brought into engagement with the complemental recoil-abutments 55-55 in the passage 19 of the stock-unit 15, and the lower rear portion of the trigger-plate 41 will have ridden onto the horizontal rear portion of the under face of the head-plate 35. The parts are so proportioned that when the barrel-unit 16 is fully in place in the stock-unit 15, as is shown in Fig. 2, a vertical stress will exist between the respective rear portions of the receiver 40 and trigger-plate 41 by what amounts to the wedge-like insertion

therebetween of the unit comprising the tensioning-fixture 27 and the head-plate 35 thereof. The proportioning of the parts is also such that when the stock-unit and barrel-unit are in the positions shown in Fig. 2, the upper portion of the tensioning-pin 34 will be flexed forwardly as shown in the said figure, thus having the effect of yieldingly holding the vertical recoil-abutments 56-56 of the barrel-unit 16 in engagement with the complemental vertical recoil-abutments 55-55 of the stock-unit 15.

Thus, by means of a structure such as that above described and shown in the accompanying drawings, not only is the barrel-unit 16 or its equivalent securely coupled to a stock-unit, but sufficient tension is applied between the two units to effectively minimize vibration and discomfort to the user. Furthermore, the structure shown and described serves to stabilize the receiver and trigger-plate such as 40 and 41 respectively, with respect to each other.

When the shock of recoil occurs, following the discharge of the firearm, the said shock will be transferred from the receiver 40 to the trigger-plate unit 41 through the engagement of the web 45 of the said receiver with the lug-like extension 49 of the trigger-plate 41. The trigger-plate, in turn, will transmit the recoil shock to the stock 15 through the intermediary of its two vertical recoil-abutments 56-56, which bear against the forwardly-facing vertical recoil-abutments 55-55 in the passage 19 in the stock-unit 15.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A takedown firearm comprising: a stock-unit formed with a vertical passage and provided with recoil-abutment means; a substantially-vertical flexible tensioning-member mounted in the said stock-unit adjacent the said vertical passage therein, one portion of the said flexible tensioning-member being anchored in the said stock-unit and another portion thereof being yielding in a direction forwardly of the said stock-unit; and a barrel-unit having recoil-abutment means engaging with the recoil-abutment means of the said stock-unit and fitting within the passage in the said stock-unit, the said barrel-unit having a forwardly-facing coupling-abutment engaging with the forwardly-yielding portion of the said flexible tensioning-member to flex the same forwardly when the recoil-abutment means of the said barrel-unit is engaged with the recoil-abutment means of the said stock-unit.

2. A takedown firearm comprising: a stock-unit formed with a vertical passage and provided with recoil-abutment means; a substantially-vertical flexible tensioning-member mounted in the said stock-unit adjacent the said vertical passage therein, the lower portion of the said flexible tensioning-member being anchored in the said stock-unit and the upper portion of the same being yielding in a direction forwardly of the said stock-unit; and a barrel-unit having recoil-abutment means engaging with the recoil-abutment means of the said stock-unit and fitting within the passage in the said stock-unit, the said barrel-unit having in its upper rear por-

tion a forwardly-facing coupling-abutment engaging with the forwardly-yielding upper portion of the said flexible tensioning-member to flex the same forwardly when the recoil-abutment means of the said barrel-unit is engaged with the recoil-abutment means of the said stock-unit.

3. A takedown firearm comprising: a stock-unit formed with a vertical passage and provided with recoil-abutment means; a tensioning-fixture unit mounted in the said stock-unit adjacent the rear of the said vertical passage therein; a substantially-vertical flexible tensioning-member having one portion anchored in the said tensioning-fixture unit and having another portion yielding in a direction forwardly of the said stock-unit; and a barrel-unit having recoil-abutment means engaging with the recoil-abutment means of the said stock-unit and fitting within the passage in the said stock-unit, the said barrel-unit having a forwardly-facing coupling-abutment engaging with the forwardly-yielding portion of the said flexible tensioning-member to flex the same forwardly when the recoil-abutment means of the said barrel-unit is engaged with the recoil-abutment means of the said stock-unit.

4. A takedown firearm comprising: a stock-unit formed with a vertical passage and provided with recoil-abutment means; a tensioning-fixture unit mounted in the said stock-unit adjacent the rear of the said vertical passage therein; a substantially-vertical flexible tensioning-member having a lower portion anchored in the said tensioning-fixture unit and having an upper portion yielding in a direction forwardly of the said stock-unit; and a barrel-unit having recoil-abutment means engaging with the recoil-abutment means of the said stock-unit and fitting within the passage in the said stock-unit, the said barrel-unit having in its upper rear portion a forwardly-facing coupling-abutment engaging with the forwardly-yielding upper portion of the said flexible tensioning-member to flex the same forwardly when the recoil-abutment means of the said barrel-unit is engaged with the recoil-abutment means of the said stock-unit.

5. A takedown firearm comprising: a stock-unit formed with a vertical passage and provided with recoil-abutment means; a tensioning-fixture unit mounted in the said stock-unit adjacent the rear end of the said passage therein and provided with both an upwardly-facing wedging-surface and a downwardly-facing wedging-surface for engagement by portions of a barrel-unit; a substantially-vertical flexible tensioning-member having one portion anchored in the said tensioning-fixture unit and having another portion yielding in a direction forwardly of the said stock-unit; and a barrel-unit having recoil-abutment means engaging with the recoil-abutment means of the said stock-unit and fitting within the passage in the latter, the said barrel-unit having adjacent its rear end a downwardly-facing portion and an upwardly-facing portion respectively having wedging engagement with the upwardly-facing wedging-surface and the downwardly-facing wedging-surface of the said tensioning-fixture unit, the said barrel-unit also having a forwardly-facing coupling-abutment engaging with the forwardly-yielding portion of the said flexible tensioning-member to flex the same forwardly when the recoil-abutment means of the said barrel-unit is engaged with the recoil-abutment means of the said stock-unit.

6. A takedown firearm comprising: a stock-

unit formed with a vertical passage and provided with recoil-abutment means; a tensioning-fixture unit mounted in the said stock-unit adjacent the rear end of the said passage therein and provided with both an upwardly-facing wedging-surface and a downwardly-facing wedging-surface for engagement by portions of a barrel-unit; a substantially-vertical flexible tensioning-member having its lower portion anchored in the said tensioning-fixture unit and having its upper portion yielding in a direction forwardly of the said stock-unit; and a barrel-unit having recoil-abutment means engaging with the recoil-abutment means of the said stock-unit and fitting within the passage within the latter, the said barrel-unit having adjacent its rear end a downwardly-facing portion and an upwardly-facing portion respectively having wedging-engagement with the upwardly-facing wedging-surface and the downwardly-facing wedging-surface of the said tensioning-fixture unit, the said barrel-unit also having a forwardly-facing coupling-abutment located in its upper rear portion and engaging with the forwardly-yielding upper portion of the said flexible tensioning-member to flex the upper portion of the same forwardly when the recoil-abutment means of the said barrel-unit is engaged with the recoil-abutment means of the said stock.

7. A takedown firearm comprising: a stock-unit formed with a vertical passage and provided with recoil-abutment means; a tensioning-fixture unit mounted in the said stock-unit adjacent the rear end of the said passage therein and comprising a fixture-member having a substantially-vertical tubular sleeve and a head-portion rigid therewith and extending substantially horizontally, a head-plate located adjacent the end of the tubular sleeve of the said fixture-member opposite its said rigid head-portion, and a substantially-vertical tensioning-pin having screw-threads adjacent one end-portion passing through the said head-plate and threaded into the sleeve of the said fixture-member, the said tensioning-pin having its opposite end-portion flexible and projecting outwardly beyond the head-portion of the said fixture-member; and a barrel-unit having recoil-abutment means engaging with the recoil-abutment means of the said stock-unit and fitting within the passage in the latter, the said barrel-unit having a forwardly-facing coupling-abutment located adjacent its rear end and engaging with the flexible end-portion of the said tensioning-pin to flex the same forwardly when the recoil-abutment means of the said barrel-unit is engaged with the recoil-abutment means of the said stock-unit.

8. A takedown firearm comprising: a stock-unit formed with a vertical passage and provided with recoil-abutment means; a tensioning-fixture unit mounted in the said stock-unit adjacent the rear end of the said passage therein and comprising a fixture-member having a substantially-horizontal head-portion at its upper end and a substantially-vertical tubular sleeve rigidly depending from the said head-portion, a head-plate located adjacent the lower end of the tubular sleeve of the said fixture-member, and a substantially-vertical tensioning-pin having an externally-threaded lower portion extending through the said head-plate and threaded into the lower portion of the sleeve of the said fixture-member, the said tensioning-pin having a flexible upper portion projecting upwardly beyond the head-portion of the said fixture-member; and a

barrel-unit having recoil-abutment means engaging with the recoil-abutment means of the said stock-unit and fitting within the passage in the latter, the said barrel-unit having a forwardly-facing coupling-abutment located in its upper rear portion and engaging with the flexible upper portion of the said tensioning-pin to flex the same forwardly when the recoil-abutment means of the said barrel-unit is engaged with the recoil-abutment means of the said stock-unit.

9. A takedown firearm comprising: a stock-unit formed with a vertical passage and provided with recoil-abutment means therein; a tensioning-fixture unit mounted in the said stock-unit adjacent the rear end of the said passage therein and comprising a fixture-member having a substantially-vertical tubular sleeve and a head-portion rigid therewith and extending substantially horizontally, a head-plate located adjacent the end of the tubular sleeve of the said fixture-member opposite its said rigid head-portion, and a substantially-vertical tensioning-pin having screw-threads adjacent one end-portion passing through the said head-plate and threaded into the sleeve of the said fixture-member, the said tensioning-pin having its opposite end-portion flexible and projecting outwardly beyond the head-portion of the said fixture-member; and a barrel-unit comprising a receiver, a barrel projecting forwardly from the said receiver and a trigger-plate coupled to the underside of the said receiver at a point substantially midway of the length of the said trigger-plate, the said receiver having a rear portion having wedging engagement with the upper surface of the said tensioning-fixture unit and the said trigger-plate unit having a rear portion having wedging engagement with the lower surface of the said tensioning-fixture unit, the said trigger-plate having recoil-abutment means engaging with the recoil-abutment means of the said stock-unit, the said receiver having a forwardly-facing coupling-abutment located adjacent its rear end and engaging with the flexible end-portion of the said tensioning-pin to flex the same forwardly when the recoil-abutment means of the said trigger-plate is engaged with the recoil-abutment means in the vertical passage of the said stock-unit.

10. A takedown firearm comprising: a stock-unit formed with a vertical passage and provided with recoil-abutment means; a tensioning-fixture unit mounted in the said stock-unit adjacent the rear end of the said passage therein and comprising a fixture-member having a substantially-

horizontal head-portion at its upper end and a substantially-vertical tubular sleeve rigidly depending from the said head-portion, a head-plate located adjacent the lower end of the tubular sleeve of the said fixture-member, and a substantially-vertical tensioning-pin having an externally-threaded lower portion extending through the said head-plate and threaded into the lower portion of the sleeve of the said fixture-member, the said tensioning-pin having a flexible upper portion projecting upwardly beyond the head-portion of the said fixture-member; and a barrel-unit comprising a receiver, a barrel projecting forwardly from the said receiver, and a trigger-plate coupled substantially midway of its length to the underside of the said receiver and having recoil-abutment means engaging with the recoil-abutment means in the passage in the said stock-unit, the said trigger-plate having a flexible lower rear-portion having wedging engagement with the under surface of the head-plate of the said tensioning-fixture unit, the said receiver having at its rear a portion having wedging engagement with the upper surface of the head-portion of the said fixture-member and also having in its rear portion a forwardly-facing coupling-abutment engaging with the flexible upper portion of the said tensioning-pin to flex the same forwardly when the recoil-abutment means of the said trigger-plate is engaged with the recoil-abutment means in the vertical passage of the said stock-unit.

11. A takedown firearm comprising: a stock-unit formed with a vertical passage therein, the said stock-unit being provided adjacent the upper rear portion of its said vertical passage with an upwardly-facing wedging-surface and adjacent its lower rear portion with a downwardly-facing wedging-surface; a barrel-unit fitting into the passage in the said stock-unit and comprising a receiver, a barrel projecting forwardly from the said receiver, and a trigger-plate coupled substantially midway of its length to the underside of the said receiver, the said trigger-plate having a rear portion having wedging engagement with the downwardly-facing wedging-surface of the said stock-unit, the said receiver having a rear portion having wedging engagement with the upwardly-facing wedging-surface of the said stock-unit; and yielding-means elastically drawing the said barrel-unit rearwardly with respect to the said stock-unit.

DAVID M. WILLIAMS.
